US0D1073847S

(12) **United States Design Patent** (10) Patent No.: **US D1,073,847 S**
(45) Date of Patent: ** May 6, 2025

(54) **FIREARM COMPENSATOR**

(71) Applicant: **BAQ Defense, LLC**, St. George, UT (US)

(72) Inventors: **Timothy Aaron Quinn**, St George, UT (US); **Clifford J. Frederickson**, St George, UT (US)

(73) Assignee: **BAQ DEFENSE, LLC**, Washington, UT (US)

(**) Term: **15 Years**

(21) Appl. No.: **29/753,994**

(22) Filed: **Oct. 5, 2020**

(51) LOC (15) Cl. **22-01**

(52) U.S. Cl.

USPC **D22/108**

(58) **Field of Classification Search**

USPC D21/567, 572-575; D22/103, 104, 108, D22/199

CPC F41A 21/32; F41A 21/34; F41A 21/36; F41A 21/325

See application file for complete search history.

(57) **CLAIM**

The ornamental design for a firearm compensator, as shown and described.

DESCRIPTION

FIG. 1 is a first perspective view of a firearm compensator; FIG. 2 is a second perspective view of the firearm compensator;

FIG. 3 is a front view of the firearm compensator;

FIG. 4 is a rear view of the firearm compensator;

FIG. 5 is a top view of the firearm compensator;

FIG. 6 is a bottom view of the firearm compensator;

FIG. 7 is a left-side view of the firearm compensator; and,

FIG. 8 is a right-side view of the firearm compensator.

The broken lines depict portions of a firearm compensator that form no part of the claimed design.

1 Claim, 5 Drawing Sheets
